UNITED STATES PATENT OFFICE.

CHARLES H. CROSSETTE, OF CHICAGO, ILLINOIS.

DESIGN FOR A NECKSCARF.

SPECIFICATION forming part of Design No. 12,220, dated April 12, 1881.

Application filed December 6, 1879. Term of patent 3½ years.

To all whom it may concern:

Be it known that I, CHARLES H. CROSSETTE, a citizen of the United States, residing at Chicago, in the county of Cook and State of Illinois, have invented and produced a new and original Design for Neckscars, of which the following is a specification, reference being had to the accompanying drawing, forming a part thereof.

10 The figure of the drawing represents a front view of my new and original design for neckscars.

15 The leading feature of my design consists in the curved outer edges of the scarf, said curve terminating in the straight edges of the same.

A represents a neckband, B a center-piece, and C C crossed aprons, secured together in the usual manner to form a flat neckscarf.

20 The inner edges of the crossed aprons are straight along their length from *a* to *b*, where they intersect at *b* with the center-piece, from

whence they extend at substantially an oblique angle to the corners *c*, from which point the outer edges of the aprons form elliptical curves extending toward the bottom of the scarf, terminating about the center of length of the same at *f* in the straight edges *e*. As the outer edges of the two aprons curve in opposite directions, the scarf presents the graceful outline of a Norman shield, and is made attractive and pleasing to the eye.

I claim—

The design for a neckscarf, the same consisting of a center-piece and two crossed aprons provided with elliptical curves, beginning at their upper edges and terminating in the straight outer edges of the same, substantially as described, and shown in the accompanying drawing.

CHARLES H. CROSSETTE.
